(57) **CLAIM**

The ornamental design for a camera ball pod, as shown and described.

DESCRIPTION

FIG. 1 is a bottom perspective view of a camera ball pod showing our new design;

FIG. 2 is a top perspective view of the camera ball pod, tilted 45 degrees to the left;

FIG. 3 is a top plan view thereof;

FIG. 4 is a bottom plan view thereof;

FIG. 5 is a right side elevational view of thereof, the left side being a mirror image of the right side shown in FIG. 1;

FIG. 6 is a reduced bottom perspective view thereof; and,

FIG. 7 is a further reduced bottom perspective view of the camera ball pod mounted on a tripod.

A camera, strap and tripod shown in broken lines in FIGS. 6 and 7 illustrate environment only and form no part of the claimed design.
